UNITED STATES PATENT OFFICE.

EDWARD B. FRITZ, OF CHICAGO, ILLINOIS.

HYDRATING BEATING AND REFINING MACHINE.

Application filed November 20, 1924. Serial No. 751,052.

To all whom it may concern:

Be it known that I, EDWARD BENTON FRITZ, a citizen of the United States, residing at Chicago, county of Cook, and State of Illinois, have invented a new and useful Improvement in Hydrating Beating and Refining Machines, of which the following is a specification.

This invention relates to a class of machines which are adapted to grinding, beating, disintegrating and reducing of material: and as a more specific application to the reduction of rags, pulp, paper stock, and such like paper making material. In the making of paper a main result to be attained is the reducing and hydrating of the fibers so that there shall be a uniformity in the product. In accomplishing this result my objects are several as will be shown by the description and claims; my primary objects are economy of space, economy of operation, economy of construction, economy of power, economy of time, maximum beating surface and gravity process.

In the paper making industry, in the preparation of the material for the paper-making machine there are several processes carried on in which the central work is done in what is commonly known to the art as a "beater," and the process consists in beating the fibers into a consistency, or attempt at uniformity. Ordinarily a device and process is used to get the material ready for the "beater," and devices are used to do the refining after it leaves the "beater." These machines require large expenditure of power, and involve loss of time in the movement from one process to the other. In applicant's device the process is one and continuous, the material is carried through its various stages by gravity, and the power is minimized. Water being a major portion of the hydrating process it assists in the operation of the machine rather than involving power to move it.

This application is an improvement upon my former application S. N. 574,402, and applies the principle of gravity treatment as set forth in that application.

The accompanying drawings illustrate one form of my invention:

Fig. 1 is a sectional elevation of the machine.

Fig. 2 is a cross section of Fig. 1 taken in the direction of the arrows 2-2.

Fig. 3 is a cross section of Fig. 1, taken in the direction of the arrows at 3-3.

As shown the mechanism consists mainly of a housing 10, preferably circular, having upon its internal walls a plurality of channels 11, in which are positioned a plurality of discs 12. Centrally operative in said housing is provided a revolvable vertical shaft 17, assembled on which are a plurality of discs 15. The discs 12 are preferably approximately quarter sections; primarily so arranged that they may be moved outwardly or inwardly for refining adjustment; secondarily, for the purpose of providing clearance around the same; and thirdly, for convenient removal and replacement. These members 12 are thickest at the wall of the housing 10 and taper inwardly as shown at 13: and I provide an adjusting means 14 for advancing or retarding the same. These discs 12 are placed in spaced relation to each other, a clearance space being provided at their interior edges. The discs 15 upon the shaft 17 are assembled thereon in spaced relation, and that spaced relation is equal to the spaced relation between the discs 12; these discs 15 are thick at the shaft and taper therefrom outwardly to the edge as indicated at 16: each taper surface is made to parallel the reversed taper surface of the discs 12, and they are arranged to intermesh and cooperate; a clearance space 24 is provided between the periphery of the discs 15 and the inner wall of the housing 10, and a clearance 18 is arranged between the inner periphery of the discs 12 and the shaft 17. I provide an opening 25 in the bottom wall of the housing 10 for the passage of the finished material into a receptacle 21 from which it may be removed through an outlet 23. I provide a supply reservoir 19 above the elevation of the housing 10 with a valve controlled channel 27 of communication between the reservoir 19 and the chamber enclosure of the housing 10: in reservoir 19 I provide agitators 20 for keeping the material delivered thereto agitated until its delivery into the chamber below: I provide an inlet 22 into the reservoir 19 through

which treated or partly disintegrated material may be delivered from a higher level as provided in my former application. The discs 12 are shown as fixed in relation to the shaft discs 15. The shaft 17 and the discs thereon are revolvable.

The material fed to this machine through the channel 27 is made to fall upon the upper of the revolving discs 15 and by reason of gravity and the tapering form of the discs the material immediately starts on a downward and outward flow, its movement being accelerated by the revolving of the rotors; passing over the periphery its course would be downward and inward by reason of the downward incline of the discs 12, the material being manipulated between the cooperating surfaces during its process downward, outward and inward, some of the material passing directly downward between the clearance space between the quarter sections; the material passing out of the chamber at 25 after having travelled its course through the repetition of its process. In the making of paper stock a very large percentage of water is used and the mass is very fluid, the intended action being to perfectly disintegrate and hydrate the fibrous material. It will be readily seen that with the device as shown any regulation may be had of the discs 12, and that a progressive refinement may be obtained, by a change in the clearance space between the revolving and the fixed elements. The surfaces of the discs are shown diagrammatically plain but they may be corrugated, or of some irregular form, as may be found most efficient within the spirit of the invention. The housing 10 may be made in halves or sections as may be found most convenient to accommodate the removal of the discs, or replacement. I do not limit myself to the specific form of regulation of the discs as shown at 14 as it is very apparent that many means may be employed for positioning and regulating these discs.

It will be readily apparent that with the mechanism as shown practically any degree of refinement may be obtained, and in the specific field of the paper industry the material being operated upon can be handled by gravity and continuously, the only limitation being the size of the machine and the speed.

Claims:

1. In a machine of the character described a vertical chamber having an inlet at the top thereof and an outlet at the bottom, the inner walls of said chamber being circumferentially channelled, and having disposed in said channels disc portions, a centrally located rotor consisting of a vertical shaft having thereon a plurality of discs the surfaces of said discs lying closely adjacent the surfaces of the wall discs, and means for feeding material to the upper portion of the chamber, whereby said material is fed by gravity to each lower area while being thrown outwardly and inwardly the revolving discs cooperating with the stationary discs to hydrate, disintegrate and refine the

fibrous material as it travels through said machine.

2. In a machine of the character described a vertical chamber having associated with the internal walls thereof a plurality of inwardly tapering disc members, a vertical rotor centrally located therein consisting of a plurality of disc elements with surfaces lying closely adjacent to and approximately coextant with the surfaces of the wall disc elements, clearance spaces between the rotor discs and the wall discs whereby material fed to the upper portion of the chamber is fed by gravity through the chamber downwardly, the rotor and wall disc elements cooperating to disintegrate and refine the mass as it travels through said machine.

3. In a machine of the character described a vertical chamber having an inlet at the top thereof and an outlet at the bottom, the inner walls thereof having associated therewith a plurality of inwardly tapering disc members spaced apart, a vertically positioned rotor centrally located in said chamber consisting of a plurality of tapering disc members spaced apart with surfaces lying closely adjacent to the surfaces of the wall disc elements, whereby material fed to the upper portion of the chamber is fed by gravity through the chamber, the rotor and wall disc elements cooperating to beat and refine the mass as it travels through said machine.

4. In a machine of the character described a vertical chamber, a rotor vertically positioned therein consisting of a plurality of tapering discs assembled thereon in spaced relation, a plurality of fixed disc members associated with the internal wall thereof, said wall discs and said rotor discs intermeshing, their surface planes lying closely adjacent each other, clearance spaces at the outer periphery of the rotor discs and at the inner periphery of the wall discs for the free passage of material therearound, said wall discs being in sections whereby material fed to the upper portion of the chamber is fed by gravity through the chamber downwardly, the rotor and the wall disc elements cooperating to beat and refine the mass as it travels through said machine.

5. In a device for the purposes described a housing containing a vertical chamber, associated with the inner wall of said chamber a plurality of removable curved plates, said plates being assembled in series wherein a single series forms substantially a continuous circle except clearance spaces to provide for adjustment.

6. In a machine of the character described a housing containing a vertical chamber, a plurality of disc members associated with the inner wall thereof, a rotor centrally functioning therein and consisting of a plurality of disc members, the disc members

of the rotor meshing with the wall disc members, their surfaces aligned and closely adjacent, and means for adjusting the spacing between said wall members and the rotor members.

- 5 7. In a device for the purposes described a housing containing a chamber, the inner wall of said chamber consisting substantially of removable plates bearing an irregular 10 surface and inwardly tapering, a rotor vertically operating therein consisting of a plurality of removable discs spaced apart and intermeshing with the wall plates, the said 15 wall plates broken in their continuity, adjusting means for altering the spacing between the rotor discs and the wall plates.

8. In a machine of the character described a housing containing a chamber having associated with its internal wall a plurality of disc members, a rotor vertically operating 20 consisting of a plurality of disc members associated on a shaft, an outlet from the bottom of said housing into a receiving receptacle, an inlet at the top of said housing, said inlet associated with a reservoir on a 25 level above said housing, agitators in said reservoir, an inlet into said reservoir communicating with a primary source of material supply.

Signed at Chicago, Illinois, this 12th day 30 of November A. D. 1924.

EDWARD B. FRITZ.
